UNITED STATES PATENT OFFICE.

ALEXANDER SUEKOFF, JR., OF CHICAGO, ILLINOIS, ASSIGNOR TO HIMSELF AND LOUIS SUEKOFF, OF CHICAGO, ILLINOIS.

MATTRESS OR CUSHION.

1,053,675.

Specification of Letters Patent. Patented Feb. 18, 1913.

Application filed January 7, 1910. Serial No. 536,908.

To all whom it may concern:

Be it known that I, ALEXANDER SUEKOFF, Jr., citizen of the United States, residing at Chicago, in the county of Cook and State 5 of Illinois, have invented certain new and useful Improvements in Mattresses or Cushions; and I do hereby declare the following to be a full, clear, and exact description of the invention, such as will enable others 10 skilled in the art to which it appertains to make and use the same.

This invention has for its object to provide a spring mattress or cushion which is very simple, cheap, durable and noiseless 15 and can be constructed and assembled with great rapidity, and consists in the features of construction and combinations of parts hereinafter fully described and claimed.

In the accompanying drawings illustrating this invention: Figure —1— is a fragmentary detail perspective view showing the spring secured at one end in the pocket of a mattress-covered fabric in accordance with my invention. Fig. —2— is a fragmentary 25 vertical section of a mattress constructed in accordance with my invention. Fig. —3— is a similar section of a cushion or pillow constructed in accordance with my invention. Fig. —4— is a fragmentary plan view 30 of a mattress or cushion cover constructed in accordance with my invention.

In the construction of spring mattresses and cushions the greatest difficulty encountered is in securing the springs in proper 35 relative position and maintaining the same in such position and at the same time to produce a noiseless mattress by preventing direct contact of the metal parts with each other. Various expedients have been resort- 40 ed to, to produce a noiseless spring mattress which at the same time should be cheap and durable but so far as I am informed all attempts to produce a cheap mattress of this character have met with failure.

45 My invention has for its particular object to provide very simple, cheap and efficient means for mounting and relatively position- 50 ing the springs in a mattress and to this end my invention consists essentially in the provision of means on the covering fabric adapted to engage the ends of the springs and secure them thereto while at the same time they are maintained properly relatively

positioned in the mattress and isolated from each other thereby so that contact between 55 adjacent springs is entirely obviated.

My invention consists in providing mat- 60 tress covers each of which consists of two or more layers A and B of a suitable strong durable fabric, such for example as ticking ordinarily employed, or such as canvas or duck, or any other fabric having the requisite characteristics. The said layers A and B of fabric are laid one upon the other and secured to each other by means of longitu- 65 dinal and transverse lines of stitching C and D respectively, the said lines of stitching C being equidistant from each other and parallel with each other and the lines of stitching D being similarly parallel with 70 each other and spaced equally as far apart as the lines of stitching C and extend at right angles to the latter. In this way I form between the two fabrics a plurality of 75 square receptacles or pockets and to permit access to the same, I cut in the layer B, of said fabric preferably diagonally of the square pockets formed between the fabrics, a slit E of less length, however, than the diagonal of the pocket and preferably also of 80 less length than the diameter of the end coil of the spring which is to be inserted in said pocket as hereinafter described. Having secured the two layers together and cut the 85 said slits E into the pockets formed between the same, I insert into the said pockets through the said slits E, the end coils F of the springs G. The said springs G are of the ordinary design generally employed for this purpose but the end coils of the wires 90 of which they are formed are preferably left free instead of being knotted in the usual manner so that the same may be readily contracted for insertion through the said slits E. The diameters of the pockets preferably 95 accord with the diameters of the end coils of the springs to be received therein so that each spring engages the peripheral walls of the pocket and is thus firmly held against lateral movement therein. After inserting 100 the said end coils of the springs into the said pockets as described, the fabric bordering the slits E is tied together by means of the thread or twine H thereby preventing escape of the contained coils therefrom. After the 105 end coils of the entire number of springs

composing the filling or core of the mattress have been inserted in the pockets of the top and bottom covering of the mattress, the edge portions of said coverings are brought together and stitched entirely around the core thus producing a sealed structure. Upon and around this structure, hair, cotton or other mattress filling materials are laid and over the whole, the finishing coverings J 10 are laid and secured in the usual manner to produce a finished mattress. The latter is tufted in the usual manner by means of the twine which may be passed entirely through the mattress as shown. The edge 15 portions of the coverings A—B are preferably taken up so as to contract the edge portions of the mattress by contracting the edge springs a little more than those disposed in the middle portion of the mattress so that 20 the top and bottom of the latter are rendered slightly convex.

By means of my construction it will be seen that the springs are maintained in proper relative position in the structure 25 and isolated from each other by interposed fabric which prevents contact between adjacent springs thereby rendering the structure entirely noiseless. The insertion of the end coils in the pockets is quickly and 30 easily effected and the mere act of insertion serves also to relatively position and secure the springs thereby minimizing labor and besides rendering necessary the use of only relatively little additional fabric in the 35 structure.

I claim as my invention:

1. In a spring mattress, means for retaining the springs in position relatively to each other to prevent relative lateral 40 movement thereof, comprising a layer of fabric provided at intervals with openings, and a backing secured to the first-named layer by means of lines of fastening means extending longitudinally and transversely 45 respectively of the latter, said layer of fabric and said backing coacting to provide a plurality of pockets therebetween accessible through said openings, the end coils of said springs adapted to be inserted through said 50 openings into said pockets.

2. In a spring mattress, means for retaining the springs in position relatively to each other to prevent relative lateral movement thereof, comprising a layer of fabric 55 provided at intervals with openings, and a backing secured to the first-named layer by means of lines of fastening means extending longitudinally and transversely respectively of the latter, said layer of fabric and 60 said backing coacting to provide a plurality of pockets therebetween accessible through said openings, the end coils of said springs adapted to be inserted through said openings into said pockets, said pockets coinciding in diameter substantially with the di-

ameters of the end coils of the springs adapted to be contained and engaged therein.

3. A cushion comprising in combination, springs and coverings, said coverings each provided at regular intervals with pockets 70 receiving the end coils of said springs, the latter entering the same through slots in the opposing faces of the coverings.

4. A cushion comprising in combination, springs and coverings, said coverings each 75 consisting of a plurality of layers of fabric secured together by lines of stitching, the intermediate spaces bordered by said lines of stitching constituting pockets, there being a slot in one wall of each of said pockets 80 through which the end coil of one of said springs is inserted, the fabric bordering said slots being secured together after the insertion of said end coil of said spring.

5. A cushion comprising in combination 85 two opposite covers each consisting of a plurality of layers of fabric secured together by lines of stitching extending longitudinally and transversely thereof and forming pockets between the layers, there being 90 slots in the opposed faces of said covers permitting access to said pockets, and coiled springs interposed between said coverings, the end coils of said springs being inserted in said pockets and securely maintained in 95 proper relative positions thereby, the edges of said coverings being secured together to form a box like structure.

6. A cushion comprising in combination 100 a plurality of coiled springs, and a covering of fabric therefor, said covering being provided with a plurality of pockets adapted to receive the end coils of the springs and maintain the same in predetermined 105 positions relatively to each other, each of said pockets being provided with an opening affording access thereto of a size to bodily receive the end of one of said coil springs.

7. A cushion comprising in combination, 110 coverings of fabric, springs interposed between the same, and pockets in said coverings adapted to receive and engage the end coils of said springs, there being slots in the opposing faces of said coverings for admitting said end coils of said springs.

8. In a mattress or cushion, the combination with a plurality of helical springs disposed contiguous to each other, of means for preventing relative displacement of said 120 springs comprising a plurality of layers of fabric, lines of stitching extending transversely to each other through said layers to form pockets between contiguous layers of fabric to receive the end coils of said springs, 125 one of said layers of fabric slitted to provide openings for the insertion of said end coils bodily into said pockets.

9. In a mattress or cushion, the combination with a plurality of helical springs dis- 130

posed side by side, their longitudinal axes substantially parallel with each other, of means for holding said springs in position relatively to each other comprising two layers of fabric, lines of fastening means 5 securing said layers together, there being pockets between said layers bordered by said lines of fastening means and each adapted to receive an end coil of one of said 10 springs, one of said layers of fabric pro-

vided with slits to permit insertion of said end coils bodily into said pockets.

In testimony whereof I have signed my name in presence of two subscribing witnesses.

ALEXANDER SUEKOFF, Jr.
